UNITED STATES PATENT OFFICE

JOSEPH JACOBS, OF BRIDGEPORT, CONNECTICUT, ASSIGNOR TO THE A. J. DONAHUE CORPORATION, OF MILFORD, CONNECTICUT, A CORPORATION

HOSE SUPPORTER

Application filed January 31, 1931. Serial No. 512,542.

This invention relates to an improvement in hose supporters and particularly to hose supporters for ladies' use in which the button-and-loop member is suspended from a link usually connected at the lower end of an elastic strap which is adapted to be secured at its upper end to a garment. Various methods have been produced for webbing the button-member of a hose supporter so as to 5 protect the wearer against contact with the metal, but in most cases the material used for supporting the button is harsh, and is uncomfortable when rubbed against the flesh.

The object of this invention is to provide a 10 guard for the button-and-loop member so as to present a smooth surface against the skin and to cover the button, so that garments are not apt to catch thereon, and the invention consists in the construction as hereinafter described and particularly recited in the claim.

In the accompanying drawings:

Fig. 1 is a front view of a hose supporter constructed in accordance with my invention;

Fig. 2 is a side view of the same;

Fig. 3 is a front view with the forward reach of the protector raised to expose the lower end of the button-and-loop member; and

Fig. 4 is a sectional view on the line 4—4 30 of Fig. 3; and

Fig. 5 is a sectional view taken on the line 5—5 of Fig. 1.

In carrying out my invention, I employ a button-member 10 and a loop-member 11, the 35 button-member being connected with a strip of webbing 12 which is suspended from a link 13 arranged at the lower end of a strip of webbing 14 and the loop-member is connected with the link 13 by a tube 22 in the usual manner. To enclose the button-and-loop 40 members I pass a strip, preferably of satin ribbon, through the link 13 so that one reach 15 extends in rear of the button-and-loop member and the other reach 16 extends downward over the face of the button-and-loop member. The corners 17 of the inner strip are folded over the lower end of the webbing 12 of the button-and-loop member and secured thereto by stitches 18. The two reaches 45 of ribbon are also secured together by stitches 50

19 just below the link 13, and the corners 20 of the outer reach are also folded together and connected by stitches 21, so as to form a pointed end corresponding to the end of the inner reach. The rear reach of the ribbon 55 presents a smooth surface to bear against the flesh of the wearer, and the front reach covers the button-and-loop so as to prevent other garments from engaging therewith.

I thus not only produce a hose supporter 60 which will present a smooth surface but will also add to the attractiveness of the device, and does not interfere with the adjustment of the supporter.

I claim:

A hose supporter comprising a link, a piece of webbing suspended from said link, a button carried by said webbing, a loop also suspended from said link, and a guard-strip of soft material passed through said link, one 70 reach extending downward in rear of the webbing carrying the button and secured thereto, the other reach extending downward over the loop-member, and the two reaches secured together near the said link. 75

In testimony whereof I have signed this specification.

JOSEPH JACOBS.
